PLASTIC COATED FABRIC OR SIMILAR ARTICLE

Jakob H. Vogel, West Orange, N.J., assignor to Inter-chemical Corporation, New York, N.Y., a corporation of Ohio

Application February 14, 1958, Serial No. 49,647

Term of patent 7 years

(Cl. D87—3)

The figure is a plan view of a coated fabric, showing my new design.

A single unit of the design is substantially comprised within the area defined by the indicating lines shown on the drawing, which unit is repeated over the surface of the fabric in the relation indicated.

I claim:

The ornamental design for plastic coated fabric or similar article, as shown.
